DESIGN FOR AN ELECTRIC HAND LANTERN

George H. Barber, New Rochelle, N. Y., assignor to
Bond Electric Corporation, Jersey City, N. J., a
corporation of Delaware

Application December 5, 1932. Serial No. 46,311

Term of patent 14 years

To all whom it may concern:

Be it known that I, GEORGE H. BARBER, a citizen of the United States, and residing in the city of New Rochelle, county of Westchester and State of New York, have invented a new, original, and ornamental Design for an Electric Hand Lantern, of which the following is a specification, reference being had to the accompanying drawing, forming a part thereof.

Figure 1 is a perspective view of the electric

hand lantern showing the front, one side and top with the hanger open or extended.

Figure 2 is a view of the lantern looking from the rear.

I claim:

The ornamental design for an electric hand lantern, as shown and described.

This specification signed this first day of December, 1932.

GEORGE H. BARBER.
